United States Patent Office

Des. 203,904
Patented Feb. 22, 1966

203,904

LIST FINDER

Hildaur L. Neilsen, 2 Juniper St., Metuchen, N.J.

Filed Nov. 24, 1964, Ser. No. 82,763

Term of patent 14 years

(Cl. D74—1)

Fig. 1

Fig. 2

FIG. 2 is a top plan view of said list finder;

FIG. 3 is a perspective view of said list finder, as seen from below and from a point toward the opposite end thereof.

The essential features of the design reside in the portions shown in solid lines on the drawing.

I claim:

The ornamental design for a list finder, as shown and described.
